RESILIENT MOUNTING FOR MICROPHONES

Harold W. Darr, Minneapolis, Minn., assignor to
The Maico Company, Incorporated, Minneapolis, Minn., a corporation of Minnesota

Application October 13, 1944, Serial No. 558,587

11 Claims. (Cl. 179—146)

1

This invention relates to a mounting for a microphone and while the invention might have application in many devices, it particularly is designed for the mounting of a microphone in a hearing aid.

One of the objections to hearing aids is what is known as case noise. This is caused by the fact that the casing of the instrument is vibrated as the person wearing it moves. The casing rubs on the clothing of the wearer and is sometimes contracted by other objects causing vibrations in the casing, which vibrations are transmitted to the microphone of the instrument creating all sorts of peculiar and confusing sounds. In some designs the sounds so created may be so powerful that the amplifier of the hearing aid may be seriously overloaded and any speech sounds coming through at the same time will be very badly distorted due to the overloaded condition created by the adventitious sounds. In considering a solution of the above objection the main problem is to eliminate or to attenuate the transmission of the casing vibrations to the microphone. It is necessary to have a good acoustical seal between the front of the microphone and the casing, otherwise sounds produced inside of the casing by the vibration thereof will leak into the microphone, thus increasing case noise. It is also necessary that the microphone be firmly mounted so that it cannot move about or flutter in the casing if the instrument is shaken with considerable force. If the microphone is not so mounted a sudden impact will throw the microphone into a fluttering condition for two or three seconds and the powerful low frequency airwaves so produced impinging on the microphone diaphragm will generate very peculiar sounds in the instrument. It is also very desirable to have the microphone mounted for easy removal.

It is an object of this invention to provide a microphone mounting of simple and efficient construction and one which will substantially eliminate case noise.

It is another object of the invention to provide a mounting for a microphone in the casing of a hearing aid or other instrument by means of which the microphone will be very firmly but resiliently held in position and which will substantially eliminate case noise.

It is also an object of the invention to provide a mounting for a microphone within a casing comprising a member of resilient material engaging the casing and supporting the microphone, said member being so constructed and arranged that it will have great compliance under

2

small vibrations and decreasing compliance under heavier vibrations.

It is still further an object of the invention to provide a mounting structure for a microphone in a casing comprising a member of resilient material disposed in the casing and engaging the same, said member supporting the microphone and having a plurality of portions engaged by the casing, said portions normally being engaged over a small area, said area however, increasing as said portions are compressed.

It is more specifically an object of the invention to provide a mounting for a microphone carried in a casing comprising a member of resilient material supporting said microphone and having a plurality of portions adapted to be engaged by said casing, some of which portions are normally out of engagement with the casing but adapted to be brought into such engagement upon the occurrence of sufficient stress between said member and casing.

These and other objects and advantages of the invention will be fully set forth in the following description made in connection with the accompanying drawings in which like reference characters refer to similar parts throughout the several views and in which:

Fig. 1 is a plan view of the rear side of front casing with microphone mounted therein;

Fig. 2 is a vertical section taken on line 2—2 of Fig. 1 as indicated by the arrows;

Fig. 3 is a partial vertical section taken on line 3—3 of Fig. 1 as indicated by the arrows;

Fig. 4 is a view partly in side elevation and partly in radial section of a supporting member used; and

Fig. 5 is a view in side elevation of a modified form of supporting member.

Referring to the drawings a portion of a casing 10 is shown in plan in Fig. 1, the same having a front wall 10a and having a side or surrounding flange 10b directly rearwardly. Lugs 10c extend inwardly from flange 10b and are apertured or tapped to receive securing screws for holding a cover 10h on casing 10. The front side 10a of the casing has an opening 10d therethrough, the same having a rabbeted portion or shallow recess 10e extending thereabout. Opening 10d may be in the form of slots formed in a grill. Casing 10 has an inwardly extending flange 10f illustrated as of substantially cylindrical form. A member 11 of resilient material is fitted snugly within the flange 10f, the same having a flat side engaging a layer of grill cloth 12 which may be made of some closely woven fabric. Said cloth 12 is

disposed against the inner side of casing 10 and extends across the opening 10d. Member 11 which is shown as annular in form, has a plurality of peripheral projections 11b illustrated as equally spaced and of semi-cylindrical form, which engage the inner wall of flange 10f. Said flange is thus engaged by member 11 at spaced points. A microphone 13 is provided, the same being shown as having a flange 13a projecting outwardly from its periphery. The diaphragm 13b of the microphone overlies flange 13a and preferably has its edge portion secured thereto in any suitable manner as by soldering or welding. Electrical conductors 13c are shown as leading from the inner side of microphone 13. Member 11 which is substantially in the form of a ring, has a slot 11a at its inner side in which the flange 13a and diaphragm 13b secured thereto are disposed and in which they are snugly fitted. Microphone 13 is thus supported in the member or ring 11. The projections 11b of member 11 are continued at one side of said member and form in effect pillars shown as cylindrical in form, and it will be noted that said projections or pillars have their flat terminal ends in different planes. Preferably alternate ones of said projections 11b will have their terminal surfaces in the same plane. A securing member 14 forming a removable part of casing 10 is provided, the same being formed of thin resilient sheet material and being substantially in the form of a flat ring. Said ring surrounds the body of the microphone but is spaced slightly therefrom at its inner side. Said ring is provided with a plurality of circumferentially spaced slots 14a and portions of metal from these slots are bent downwardly to form tongues or resilient prongs 14b, the terminal ends of which project outwardly as shown at 14c, and are disposed in a slot 10g extending about the inner side of flange 10f. The inner flat surface of ring 14 normally engages the terminal surfaces of the longer projections 11b. Member or ring 11 is thus normally under some compression. The ring 14 is so constructed that it can be placed over the microphone 13 into engagement with the projections 11b and the circumferentially spaced prongs or tongues 14b then pressed or snapped into position in flange 10f. The microphone 13 is thus mounted for convenient and quick removal by merely prying the ring 14 from its securing position.

In operation the microphone will be supported as described and will be very firmly held in position in the member or ring 11. The microphone is also indirectly held by the ring 14 which engages and holds in place the member 11. Any vibrations occurring in the casing 10 will be communicated to the ring 14 which will in turn transmit them to the projections 11b of member 11. There is a comparatively small area of these projections 11b engaged by the ring and the compliance or yielding effect of these projections will be quite large. Any small vibrations therefore, will be taken up or absorbed by the yielding or resilient action of the projections 11b. Should greater vibrations or shocks occur in casing 10, the projections 11b normally in contact with ring 14 will be so compressed that said ring will move into position to engage the other projections 11b. The vibrations will thus be transmitted to a greater number of projections 11b and the compliance of member 11 and its projections 11b will be reduced. The vibrations will be effectively damped by the resilient action of the projections 11b. The projections 11b

could of course, be arranged to be progressively engaged by the ring 14.

In Fig. 5 a different form of resilient member is shown comprising a member 17 which is likewise in the form of a ring and of the same construction as member 11 except that instead of the cylindrical projections having flat terminal surfaces, projections 17a are provided having semi-cylindrical peripheries at the sides of ring 17 but with the portions projecting at one side of member 17 having converging sides with small or pointed terminal ends. The ring 14 will engage the tops of the projections 17a and it will be seen that there will be quite a small area normally in contact with ring 14. When slight vibrations occur in the casing 10 the compliance or yielding effect of the projections 17a will be quite large and said vibrations will be quickly absorbed by the yielding or resilient effect of said projections. The greater the vibrations in the casing, the greater will be the compression of projections 17a and the greater will be the area of contact between ring 14 and said projections. It will thus be seen that in both of the modifications shown there is a greater area of contact between the casing and member 11 during heavy vibrations or shocks than during very light vibrations. The vibrations are thus effectively absorbed and case noise is substantially eliminated.

The aim of the mounting is of course, to secure an acoustical low pass filter between the microphone and the casing. The more effective the attenuation of the filter, the less vibration of the casing is transmitted to the microphone. Two of the main factors in such a filtering action are the mass of the microphone casing and the compliance of the resilient mounting ring. Ideally the mass of the microphone should be as great as possible. This of course, cannot be achieved because the hearing aid must be made as light as possible. Also ideally the compliance of the mounting ring should be as great as possible. This also cannot be accomplished because the microphone would then move about or flutter. In the present structure the rubber or body of member 11 is stressed only in compression. It thus cannot fail mechanically and there is no danger of the microphone falling or moving about in the casing. The ring 11 has been so constructed as to offer a very small area of contact to resist small vibrations but to offer a larger area of contact to greater vibrations. Two opposing objectives have thus been achieved. It could be said that the compliance or yielding effect of the yielding member 11 varies inversely with the applied force or force of the vibrations. This inverse function is not necessarily a linear function but could be made in various ways so as to be non-linear.

From the above description it will be seen that I have provided a very simple, compact and efficient mounting for a microphone. The microphone is mounted so that it can be easily removed and yet it is so mounted that it is firmly supported in the casing and cannot move about or flutter therein. The structure is also such that any vibrations of the casing are not transmitted to the microphone and case noise is thus eliminated. The device has been amply demonstrated in actual practice, found to be very successful and efficient and is being commercially made.

It will of course, be understood that various changes may be made in the form, details, ar-

angement and proportions of the parts without departing from the scope of applicant's invention, which generally stated, consists in a device capable of carrying out the objects above set forth, in the parts and combinations of parts disclosed and defined in the appended claims.

What is claimed is:

1. A mounting structure for a microphone having in combination, a casing, a microphone within said casing, a resilient member supported by said casing and supporting said microphone, said member having a small area normally engaged by said casing and a larger area engaged by said casing upon vibration of said casing.

2. A mounting structure for a microphone having in combination, a rigid casing, a microphone within said casing, a resilient member supported by said casing and supporting said microphone, said member having a small area normally engaged by said casing and having another area normally out of engagement with said casing but constructed and arranged to engage said casing under stress.

3. A mounting structure for a microphone having in combination, a casing, a microphone within said casing, a resilient member supported by said casing and supporting said microphone, said resilient member having a plurality of portions normally engaged by said casing and a plurality of portions normally out of contact with said casing but disposed adjacent thereto and adapted to be engaged by said casing upon sufficient compression of said first mentioned portions.

4. A mounting structure for a microphone having in combination, a casing, a microphone within said casing, a resilient member supported by said casing and supporting said microphone, said resilient member having a portion with a small area normally engaged by said casing and constructed and arranged to have a greater area engaged by said casing upon compression of said portion.

5. A mounting structure for a microphone having in combination, a casing, a microphone, a member of resilient material having one side engaging said casing and disposed about said microphone, said microphone having a portion disposed in said member for supporting said microphone, said member having at a substantially opposite side a plurality of circumferentially spaced casing engaging projections having converging sides with pointed terminal ends.

6. A mounting structure for a microphone having in combination, a casing, a microphone, a member of resilient material between said microphone and casing, said member having at one side a plurality of spaced portions, some of which are normally engaged by a part of said casing and a part of which are only engaged during vibration of said casing.

7. A mounting structure for a microphone having in combination, a casing, a member of resilient material having one side thereof engaging said casing, a microphone supported by said member,

said member having a portion of comparatively small area at its opposite side engaged by said casing, said member having an additional portion at said opposite side normally adjacent but out of contact with said casing but adapted to be engaged by said casing upon vibration thereof.

8. A mounting structure for a microphone having in combination, a casing, a ring of resilient material engaging said casing, a microphone supported by said ring, said ring having spaced projections at its opposite side and means supported by said casing and engaging a small area of said projections but constructed and arranged to engage a larger area upon vibration of said casing.

9. A mounting structure for a microphone having in combination, a casing, a member of resilient material having one side engaging said casing, a microphone supported by said member and held against lateral movement thereby and a member removably engaging said casing and engaging a substantially opposite side of said first mentioned member holding the same in compression, said first mentioned member having a small area normally engaged by said second member and having a larger area adapted to be engaged by said second member upon compression of said resilient member.

10. A mounting structure for a microphone having in combination, a casing, a microphone, resilient means engaging said casing and disposed about said microphone, said microphone having a portion supported in said resilient means, said resilient means additionally engaging said casing over a small area of said means, said second member being formed as a ring of sheet material having prongs, said flange having a recess in which said prongs engage.

11. A mounting structure for a microphone having in combination, a casing having a flange projecting at one side and provided with a groove, a microphone, a ring of resilient material disposed about said microphone, said microphone having a projecting portion disposed in said ring, said ring engaging said side, a ring of thin resilient material having spaced prongs projecting substantially at right angles therefrom having terminal portions adapted to engage in said groove, said ring overlying and engaging said first mentioned ring.
